PRESSER-FOOT FOR SEWING MACHINES

Rudolph J. Sailer, Townley, N. J., assignor to The
Singer Manufacturing Company, Elizabeth,
N. J., a corporation of New Jersey

Application April 27, 1937, Serial No. 139,119

11 Claims. (Cl. 112—235)

This invention relates to presser-feet for sewing machines and has for an object to provide a presser-foot which is specially adapted to cooperate with the feed-dog in uniformly feeding past the stitching mechanism heavy or coarse material having cross-seams therein, and to accommodate itself closely to the surface of the material so as to effectively control the same to prevent the skipping of stitches at the cross-seams.

It is a further object of the present invention to provide a presser-foot so constructed that it will readily ride over heavy cross-seams without presenting any obstructions which would tend to 15 impede the feeding of the material and require the assistance of the operator in pulling on the work in rear of the sewing point.

Heretofore it has been customary, in presser-feet having two independent pivotally mounted work-engaging foot-sections in tandem arrangement, to incline or upturn the toe-portion of the rearward foot-section so that it will not act as an obstruction against which the cross-seams abut, but will function to tilt the foot-section and permit cross-seams to pass thereunder. In cases where the cross-seams are exceptionally heavy, such as encountered in the manufacture of overalls, wind-breakers, etc., the inclined toe-portion of the rearward foot-section offers considerable resistance to the passage of these cross-seams. In the present case, this fault is largely overcome by suitably connecting the two foot-sections together so that the downward tilting of the forward foot-section automatically raises the toe of the rearward foot-section, thereby eliminating any obstruction and minimizing the friction between the presser-foot and the work. Further features of the invention will, in part, be obvious and, in part, be hereinafter described.

In the accompanying drawing,

Fig. 1 is a side elevation of a sewing machine presser-foot embodying the invention.

Fig. 2 is a top plan view of the presser-foot.

Fig. 3 represents a vertical sectional view taken substantially on the line 3—3, Fig. 1, disclosing the manner in which the forward foot-section is pivotally supported on the bifurcated end of the yoke.

Fig. 4 is a disassembled perspective view of the presser-foot illustrating the details of construction thereof.

Figs. 5, 6 and 7 are views similar to Fig. 1 showing, progressively, various positions of a cross-seam passing under the presser-foot.

According to the preferred embodiment of the invention illustrated, the presser-foot comprises a shank 1 adapted to be secured as usual to the conventional vertically movable presser-bar 2 of a sewing machine having a reciprocating needle-bar carrying needles 3, which operate in the usual

needle-apertures in the throat-plate 4, which latter is slotted as usual to admit the conventional serrated sections of the four-motion feed-dog 5.

The presser-foot shank 1 is formed at one end with a depending rectangular portion 6 apertured, as at 7, to receive a transverse trunnion pin 8 on which is pivotally supported for limited vertical turning movement a yoke 9. The forward end of the yoke 9 is bifurcated and, when assembled, is adapted to straddle the depending portion 6 of the shank 1.

Pivoted to the free ends of the furcations 10 and 11 of the yoke 9 is a forward or primary foot-section 12. Rising from the primary foot-section 12 are the spaced longitudinally disposed ears 13 forming between them a channel adapted to receive the forward end of the yoke 9.

These ears 13, which prevent lateral displacement of the primary foot-section with respect to the shank 1, are suitably apertured, as at 14, to receive the headed pivot-studs 15 which are retained in the apertures 16 in the yoke furcations 10 and 11 by the screws 17 threaded into the apertures 18 provided in the ears 13 of the primary foot-section 12. As clearly illustrated in Figs. 2—25 and 3, the primary foot-section is provided with the usual needle-apertures 19 and with the inclined channel 20 formed in its under surface.

Pivoted to the rearward portion of the yoke 9 is the rearward or secondary foot-section 21. Rising from the secondary foot-section 21 are the spaced longitudinally disposed ears 22 provided with apertures 23 which receive the transverse trunnion pin 24 adapted to fit snugly in the aperture 25 provided in the rearward portion of the yoke 9. It will be noticed in Fig. 4 that the longitudinal axis of the trunnion pin 24 is substantially parallel to a line passing through the axis of each of the pivot-studs 15, and also that the trunnion pin 24 is positioned transversely of the foot-sections.

Preferably formed on the spaced ears 22 of the secondary foot-section 21 are two forwardly extending projections 26 which fit into suitably shaped notches or recesses 27 formed in the rearward ends of the ears 13 of the primary foot-section 12. The projections 26 and the cooperating notches 27 provide a hinge connection between the primary and secondary foot-sections which functions to forcibly raise the toe of the secondary foot-section when a cross-seam, as it passes beyond the pivotal point of the primary foot-section, raises the heel thereof. It will be observed that the hinge connection also serves to retain the treads of both foot-sections substantially flush at their adjacent edges. Obviously any suitable means may be used in place of the herein disclosed projection and notch for operatively connecting the two foot-sections together.

As illustrated in Fig. 5, the cross-seam S has

come in contact with and is passing under the primary foot-section 12 and has caused a slight tilting of said foot-section without disturbing the normal position of the secondary foot-section 21 whose tread still rests upon the material. As the material is advanced by the feeding mechanism, (see Fig. 6), the cross-seam S passes beyond the pivotal point of the primary foot-section 12, with the result that the latter is reversely tilted and, through its hinge connection with the secondary foot-section 21, the toe of the latter is forcibly raised and does not obstruct the passage of the cross-seam S. In Fig. 7 it will be seen that the tread of the primary foot-section 12 rests upon the material after the cross-seam S passes beyond the pivotal point of the secondary foot-section 21. It will be obvious from Figs. 5, 6 and 7 that the toe of the secondary foot-section does not interfere at any time with the passage beneath the presser-foot of the material or cross-seams. Furthermore, the adjacent work-engaging edges of the foot-sections remain at all times substantially horizontally coplanar or, in other words, the adjacent heel or rear work-engaging edge of the primary foot-section 12 and toe or forward work-engaging edge of the secondary foot-section 21 are maintained at substantially the same levels regardless of the position of the cross-seam S beneath the presser-foot.

30 In order to maintain the toe of the primary foot-section 12 elevated as high as possible when the presser-bar is raised, a coil-spring 28 is preferably provided. This coil-spring is housed in a cavity 29 formed in the shank 1. The lower end 35 of the coil-spring bears against the yoke 9 and yieldingly maintains the furcations 10 and 11 thereof in contact with the shoulders 30 of the shank 1. It is desirable when sewing material having exceptionally heavy cross-seams that the 40 foot-sections have a comparatively large amount of pivotal movement. To accomplish this, the yoke of the present presser-foot is preferably slightly arched, as clearly disclosed in Figs. 4 and 5.

45 While I have shown and described in detail a preferred embodiment of the invention, it is to be understood that the invention is not limited to a device having the details of construction and precise mode of operation described. To 50 handle seams of different character and work of various thicknesses, the pressure applying sections of the foot may be varied in form and arrangement within the scope of the invention, as will be understood by those skilled in the art.

55 Having thus set forth the nature of the invention, what I claim herein is:

1. A presser-foot comprising a shank, a plurality of pivotally mounted foot-sections sustained by said shank, and means constantly connecting 60 said foot-sections together and rendered effective by the tilting of one foot-section for reversely tilting another of said foot-sections.

2. A presser-foot for sewing machines comprising a plurality of foot-sections, a yoke to which said foot-sections are independently pivoted, a shank to which said yoke is pivoted, means interposed between said shank and yoke for yieldingly raising the forward end of the latter, and means for limiting movement of the yoke.

3. A presser-foot for sewing machines comprising a shank, a yoke attached to said shank, a foot-section pivoted to said yoke and having ears formed with notches therein, and a second foot-section pivoted to said yoke and having ears formed with projections thereon adapted to be

received by the notches in said first-named foot-section.

4. A sewing machine presser-foot having, in combination, a shank formed with a depending portion, a bifurcated yoke attached to and straddling said depending portion, a spring interposed between said shank and yoke for yieldingly raising the forward end of the latter, a primary foot-section pivoted to the bifurcated end of said yoke, and a secondary foot-section pivoted to the rearward end of said yoke. 5

5. A sewing machine presser-foot comprising a shank formed with a depending portion, a bifurcated yoke attached to and straddling said depending portion, means interposed between the shank and yoke for raising the forward end of the latter, a primary foot-section pivoted to the bifurcated end of said yoke, a secondary foot-section pivoted to the rearward end of said yoke, and means connecting said foot-sections together 15 and rendered effective by the tilting of one foot-section for reversely tilting the other foot-section. 15

6. A unitary presser member for sewing machines having, in combination, a shank, a single yoke pivoted to said shank, a plurality of foot-sections independently pivoted to said yoke, and means at all times operatively connecting said foot-sections together. 25

7. A sewing machine presser-foot comprising a shank, and a plurality of pivotally mounted foot-sections sustained by said shank, one of said foot-sections having a notch formed therein, and another of said foot-sections provided with a projection adapted to constantly engage the notch formed in said first-named foot-section. 30 35

8. A presser mechanism for sewing machines comprising a presser-bar, a shank carried by said presser-bar, a plurality of pivotally mounted foot-sections sustained by said shank, all of said foot-sections having a substantially equal pressure applied thereto during the operation of the machine, and means connected to one of said foot-sections for moving another of said foot-sections about its pivot. 40

9. A presser mechanism for sewing machines comprising a presser-bar, a presser-foot having a shank secured to said presser-bar, said presser-foot including a plurality of foot-sections mounted upon substantially parallel axes for limited pivotal movement, and means constructed and arranged to maintain at all times the adjacent work-engaging edges of the foot-sections substantially horizontally coplanar. 45 50

10. A presser mechanism for sewing machines comprising a presser-bar, a presser-foot having a shank secured to said presser-bar, said presser-foot including a plurality of foot-sections mounted upon substantially parallel axes for limited pivotal movement, said parallel axes being arranged transversely of the foot-sections, and means constructed and arranged to maintain at all times the adjacent work-engaging edges of the foot-sections at substantially the same levels. 55 60

11. A presser-foot having, in combination, a shank, a pivotally mounted forward foot-section sustained by said shank, a pivotally mounted rearward foot-section sustained by said shank and positioned in alignment with said forward foot-section, and means at all times connecting the heel of the forward foot-section with the toe of the rearward foot-section, said means rendered effective by the tilting of one foot-section for reversely tilting the other foot-section. 65 70 75
